ADVERTISING DEVICE

Filed July 10, 1931

UNITED STATES PATENT OFFICE

GUSTAVE O. MATTER, OF PORTLAND, OREGON

ADVERTISING DEVICE

Application filed July 10, 1931. Serial No. 549,869.

My invention relates to a display device, and particularly to a device of that character suitable for advertising display. In general terms, the invention embodies a continuously moving display carrier of the rotary drum or polygon type. Also, a housing in which the drum is incased. The drum carries display matter which is removable from the drum in order that its character may be changed from time to time. The casing is provided with an opening or window before which the display passes for viewing.

The drum is so constructed that the display matter is arranged in obliquely disposed lines on the periphery thereof, and as the drum rotates the left hand portion of the matter displayed makes its appearance first, followed by the balance thereof in regular order from left to right. As this manner of display follows the practice of reading the printed word, it is obvious that such an arrangement will greatly aid the viewer in reading such matter, especially is this true when it is considered that the display device or drum is continuously revolving.

Aside from the foregoing advantages, the presentation of the display matter in the manner outlined will arouse the curiosity of the viewer to see what follows, and it will be an urge to him to view the entire display, thereby making the device particularly useful for advertising purposes.

Other advantages will appear upon reading the specification, aided by the drawing herein, wherein:

Figure I is a front elevation of the invention.

Figure II is the vertical section of Figure I indicated by the vertical section line II-II of that figure.

Figure III is similar to Figure II, and is a modification of the construction shown in the preceding figure.

Figure IV is a front elevation of a modified display carrier.

Figure V is the vertical section of Figure IV indicated by the vertical section line IV-IV of that figure.

Figure VI is a front elevation of another modification of this invention.

Figure VII is the vertical section of Figure VI indicated by the vertical section line VII-VII of that figure.

Similar numerals refer to similar parts throughout the several views:

Referring now to the drawing, 1 represents a base which carries the casing 2 provided lengthwise of its front portion with an observation window or aperture 3. Within the casing and at each end of base 1 is mounted an upright standard or shaft support 4 which supports shaft 5. Shaft 5 is secured against movement, rotary or otherwise, by the set screws 6.

Mounted for revolution on shaft 5 is a display carrier or drum 7. Drum 7 is provided at one end with a spider 8 and at the other end with a spider 9. These spiders are journaled upon shaft 5, and support the drum for revolution thereon. Spider 9 is provided with a grooved pulley 10, the purpose of which will appear hereafter.

In Figures I and II, drum 7 is a cylindrical member. A number of equally spaced guides or display plate holders 11, each oblique to an intersecting radial plane, are arranged upon the periphery of the drum. These guides have their outer edges so constructed that the ends of display plates 12 may be inserted thereunder. The plates, as disclosed in this instance, are shown to have displayed thereon certain letters of the alphabet, and are arranged in separate lines, each line being located between two cooperating guides in order to form either sentences, parts of sentences or individual words. As disclosed, the plates are arranged in lines to display the words Overcoat and Mens hat. However, it is to be understood that the matter to be displayed upon the drum is purely a matter of choice and selection, and to a great extent is governed by the use to which the present apparatus is put. It is to be understood that the slides are inserted under the ends of the respective guides and are slid to the position they are to occupy.

From the foregoing it will be seen that the drum is revoluble upon shaft 5, and as it revolves the matter displayed thereon continuously passes and repasses behind the window.

dow or opening 3 whose major dimension is parallel to the axis of such drum. Due to the fact that the matter displayed on the drum is arranged obliquely thereon, it will be evident, in cases of words, sentences and the like, that the letters comprising such words, etc., will appear consecutively, commencing with the first letter, or as is natural in reading, commencing at the left of the 5 word and proceeding to the right. Of course it is necessary that drum 7 revolve in the correct direction in order that this may be done, and this direction is upwardly when viewed through window 3, or to the left, 10 counter-clockwise and as the arrow points in Figure II. It is also desirable that the drum be rotated at a steady rate of speed, and at a degree of speed that will enable the viewer to readily comprehend the matter displayed. In ordinary cases, it will be found that an electric motor will be most suitable as a means for driving drum 7, and in the present instance such means is provided in a motor 13. Motor 13 has a reduction gear 15 20 driving a grooved pulley 15, which is connected by a belt 16 to the pulley 10 associated with drum 7.

Figure III illustrates a modification of drum 7. In this figure drum 17 is constructed 30 of transparent or translucent material. It is supported for rotation upon shaft 19 by spiders 18. The purpose for making drum 17 of material of the character specified is to provide a way whereby the display matter 35 appearing upon the face thereof may be illuminated. This is done by providing an illuminating member within the interior of the drum which will direct light rays through the drum toward the opening or window 3 in casing 2. The illuminating member in 40 this view consists of an electric lamp 20 mounted in socket 21 of the reflector base 22. Leads to the lamp 20 pass through the reflector base into and through shaft 19 (which is bored for that purpose) to an energy source. Base 22 supports the reflector 45 23, designed to direct the light rays from lamp 20 toward window 3 of the casing.

Figures IV and V present a modification in 50 the construction of the display carrier. The display carrier indicated in its entirety by the numeral 24, is composed of two webs 25 and 26 which are held in proper spaced relationship with one another by the spiral guides 55 or holders 27. Webs 25 and 26 are designed to rotate upon one or the other of the shafts 5 or 19. Web 26 is provided with a grooved pulley 28 having the same purpose as previously described pulley 10. Guides 27 are 60 designed to hold removable display plates 29, and for this purpose their lateral edges are provided with grooves, the positions of which are indicated by the edge portions 30 of such plates. Plates 29 are intended to be arranged in lines for any desired display, and

as previously described for plates 12, are placed in oblique formation on carrier 24, and their appearance before the window is the same as that of the previously described plates. If desired plates 29 may be formed 70 of a transparent or translucent material. In which event the carrier could be furnished with an illuminating device similar to that previously described.

Figures VI and VII illustrate another 75 modification of my invention. In this instance the drums are replaced by an endless curtain 31 which passes about two rollers 32 and 33 respectively. The rollers and curtain are mounted in a casing 34 which has in one side a viewing window 35. The curtain 31, if desired, may be made of translucent material in order that the display arranged thereon may be illuminated by some illuminating means located within the confines of the curtain. The display 36 on the curtain is arranged obliquely so that the display will have the same visual effect as that of the previously described drums and display carriers. This display device lends itself admirably for mounting upon vehicles, in cramped quarters, and for mounting upon vertical faces, such as walls, and likewise as a warning sign over doorways, gates and the like. 95

What I claim:—

1. In a display device, a display drum continually rotating about its axis, a casing normally concealing said drum and provided with a view aperture whose major dimension from one end to the other parallels the axis of said drum, said drum having guides located upon its periphery, each guide being obliquely disposed with regard to an intersecting radial plane, including means for each adjacent pair of guides to hold a line of display matter therebetween, and the obliquity of the guides causing each display line to pass before the view aperture in the order that it is to be read, commencing with one end thereof and continuing to the other end. 100

2. In a display apparatus, a display carrier having display lines arranged thereon in parallel order, each line being disposed obliquely with regard to a horizontal plane of vision, means normally concealing said carrier and provided with an elongated aperture for viewing the aforesaid lines, the length and width of said aperture being substantially that of each line, mechanism providing a relative movement between said carrier and said concealing means whereby said lines are presented before said aperture one after another, the obliquity of each line causing it to progressively pass before said view aperture, commencing with one end thereof and continuing to the other. 115 120 125

3. In a display apparatus, a display carrier having display lines arranged thereon 130

in parallel order, means normally concealing said carrier and provided with an elongated aperture for viewing the aforesaid lines, said aperture having a length equal to each line and a width substantially equal to each line, the latter dimension tending to limit observation of the display matter to essentially one line at a time, said lines and the longitudinal confines of said aperture being arranged obliquely with regard to one another, including means for imparting a relative movement therebetween whereby the aforesaid relative obliquity existing between said line and aperture causes each line to progressively pass before said aperture, commencing with one end thereof and continuing to the other.

4. In a device of the character described, an endless display carrier designed for continuous movement whereby the display carrier thereby repeatedly passes in exhibition, display matter arranged upon said carrier in superposed lines, a casing normally concealing said carrier, said casing being provided with an aperture having a major dimension coextensive with the length of each display line and a minor dimension limited substantially to the width of the display lines, the latter dimension being the width of the aperture tending to restrict observation of the display matter to substantially one line at a time, and the display lines each being obliquely arranged upon said carrier in order that they pass before said aperture in the manner they are to be read, commencing at one end thereof and continuing to the other.

5. In a display apparatus, a continuously moving display carrier, said carrier being essentially an endless display device designed to repeatedly exhibit display matter, said carrier carrying display matter arranged in parallel lines for exhibition one line after another, a casing concealing said carrier, said casing having an elongated aperture for viewing the aforesaid display, the width and length of such aperture being approximately equal to each display line, and the lines being arranged obliquely with regard to said aperture thereby causing each line to appear behind the aperture in the order that it is to be read, commencing at one end thereof and continuing to the other.

GUSTAVE O. MATTER.
